UNITED STATES PATENT OFFICE.

GEORGE EHRHARDT, OF SACRAMENTO, CALIFORNIA, ASSIGNOR OF ONE-THIRD TO
MICHAEL J. SILVA, OF SACRAMENTO, CALIFORNIA.

DOOR OR WINDOW SECURER.

1,255,996.

Specification of Letters Patent. Patented Feb. 12, 1918.

Application filed April 12, 1917. Serial No. 161,522.

To all whom it may concern:

Be it known that I, GEORGE EHRHARDT, a citizen of the United States, residing at Sacramento, in the county of Sacramento and 5 State of California, have invented certain new and useful Improvements in Door or Window Securers; and I do declare the following to be a full, clear, and exact description of the invention, such as will enable 10 others skilled in the art to which it appertains to make and use the same.

This invention relates to a door or window securer, and has for an object the provision of a substitute for the well known 15 sliding bolt or lock on doors, and the pivoted sash fasteners on windows, or as is readily understood, may be used in combination with said locks and fasteners.

Another object is to provide a simple and 20 efficient device which may be conveniently carried by tourists or travelers and used on the doors and windows of the rooms they occupy.

A further object is to provide a device 25 which may readily be used to securely lock a door whether the door and frame are in the same plane or not.

With these and numerous other objects in 30 view, my invention consists of the novel features of construction, combination, and arrangement of parts which will be herein-after referred to and more particularly pointed out in the specification and claim.

In the accompanying drawing:

35 Figure 1 is a front elevation of a door and frame with my lock applied;

Fig. 2 is a horizontal section on the line 2—2 of Fig. 1;

40 Fig. 3 is a horizontal section of a door and frame in which the faces thereof are not flush and with my lock applied;

Fig. 4 is a perspective view of one part 45 of the securer; and

Fig. 5 is a vertical section of two window sashes with my lock applied thereto.

Referring now more particularly to the drawing, and with particular reference to Figs. 2 and 3 showing a door jamb or frame 1 and a door 2, and to Fig. 5 in which an 50 upper and lower window sash 3 and 4 are shown, the door or window securer is indicated at 5 and consists of a threaded bolt 6 having at one end and formed integrally therewith a flat head portion 7 which has 55 one of its flat faces disposed in a common

plane with the periphery of the bolt for a purpose to be hereinafter described, and on the extreme end of the head portion 7 is a plurality of right angularly disposed spurs or teeth 8.

A brace 9 semi-circular in shape is formed from a short bar uniformly curved its entire length and having feet 10 and 11 disposed in the same plane and adapted to engage the adjacent faces of the door and frame or 60 those of two window sashes, said brace being provided midway its length with an enlarged tapered portion having a tapered aperture 12 therethrough whose large end opens into the space between the feet 10 and 11, said aperture being adapted for the reception therethrough of the threaded bolt 6 as will be hereinafter described. A winged 65 nut or similar fastener 13 is threaded on the bolt on top of the brace 9 to force the feet 70 against the door and jamb or the window sashes.

In applying the securer to a door whether 75 it is flush with the frame as shown in Fig. 2, or below the frame as shown in Fig. 3, 80 the flat head portion 7 is inserted between the door 2 and the jamb or frame 1 and the spurs or teeth 8 are embedded in said jamb or frame as shown. After the door has been 85 closed the brace 9 is mounted on the threaded bolt 6 by passing said bolt through the tapered aperture 12 in said brace and moving it toward the door and frame until the feet 10 and 11 contact with said door and frame, after which the winged nut 13 or 90 other suitable fastening element is threaded onto the bolt 6 to prevent the brace from being forced off of said bolt.

When it is desired to use this securer on 95 a window it will only be necessary to lower the upper sash 3 and raise the lower sash 4, after which the flat head portion 7 may be easily secured to the frame of the upper sash by embedding the spurs or teeth 8 therein as shown, and then the sashes move 100 to their original position, this being permitted because of the fact that one face of the flat headed portion 7 is disposed in a common plane with the periphery of the bolt, thereby presenting a smooth face for 105 the lower sash 4 to engage as it is moved to either closed or open position. It is readily seen that if the periphery of the bolt 6 and one face of the flat headed portion 7 were 110 not in the same plane that upon raising the

window sash 4 a projection which is found in other types of securers would prevent such raising of the window sash 4. After the window has been closed, the brace 9 is 5 mounted as hereinbefore stated and the threaded winged nut applied, and when assembled will appear as shown in Fig. 5.

From the foregoing description of the construction and method of forming my new and improved door or window securer, the manner of applying the same to use, and its operation will be readily understood, and it will be seen that I have provided a simple and efficient device of this character for carrying out the objects of the invention. 15

I claim:—

In a door or window securer, the combination with a threaded bolt having a flat headed portion on one end and rightangu-

larly bent spurs on the end of said portion; 20 of a short metal bar bent to form a semi-circular brace having flat extremities disposed in the same plane, said bar having a centrally disposed enlarged tapered portion through which extends a tapered aperture 25 whose large end opens into the concave side of the brace, said bolt being extended through said aperture from the concave side of the brace, and a nut threaded on said bolt for holding said extremities in close contact 30 with the portions to be locked or secured.

In testimony whereof I have hereunto set my hand in the presence of two subscribing witnesses.

GEORGE EHRHARDT.
